UNITED STATES PATENT OFFICE.

JAMES DUNLOP, OF CHICAGO, ILLINOIS, ASSIGNOR TO KAESTNER & HECHT COMPANY, OF CHICAGO, ILLINOIS, A CORPORATION OF ILLINOIS.

ELEVATOR-DOOR LOCK.

Application filed August 16, 1924. Serial No. 732,399.

My invention pertains to improvements in elevator door locks, and more specifically to door locks automatically controlled by means on the elevator cage.

5 One of the objects of my invention is to provide a novel elevator door lock having a locking member adapted to be automatically disengaged from the door catch, but which is held in locking position when the door is closed and cannot be disengaged except upon an attempt to open the door.

10 A more detailed object is to provide an elevator door lock having a latch operating means which tends to move the latch out of engagement with the door catch when the cage is at the landing, but which is opposed by the mass of the door and is ineffective until an attempt to open the door is made to partially withdraw the catch, and is incapable 15 of retaining the latch in withdrawn position when the door is again closed.

15 Another object is to provide an elevator door lock of novel construction having a pair of switches which are connected in series in one of the control circuits of the elevator system, and are closed at the same time only when the door is closed and latched.

20 A specific object is to provide an elevator door lock having a latch adapted to be moved into and held in locking position by the door catch and to be disengaged from said catch by an electromagnet after or simultaneously with a slight withdrawal of the catch; and having a pair of switches controlling the operation of the cage, said switches being adapted to be closed respectively by the catch as the latter enters the lock, and the latch as the latter engages the catch, thereby insuring that the door is 25 closed and locked before the cage can move away from the landing.

25 A further object is to provide a lock of the above character which can be assembled in a number of ways to suit the varying requirements of different elevator installations.

30 Another object is to provide means for preventing the switches in the door lock from being injured by manual tampering when the door is open.

35 Still a further object is to provide a door lock for electric elevators which is constructed of but a small number of moving parts, simply and compactly arranged, and which

is reliable, efficient, and neat in appearance.

Ancillary objects and advantages will become apparent as the description proceeds.

In the accompanying drawings, Figure 1 is a front view of a door lock constructed in accordance with my invention, one cover plate being removed to show the interior of the lock.

Fig. 2 is a view showing a slightly different assembly.

Fig. 3 is a sectional view taken along line 3-3 of Fig. 1.

Fig. 4 is a left side view of the assembly shown in Fig. 2 with the door catch removed.

Fig. 5 is a simple diagrammatic representation of an electric elevator illustrating the use and operation of the lock.

While my invention is susceptible of various modifications and alternative constructions, I have shown in the drawings and will herein describe in detail the preferred embodiment, but it is to be understood that I do not thereby intend to limit the invention to the specific construction disclosed but aim in the appended claims to cover all forms falling within the spirit and scope of the invention.

Referring to the exemplary embodiment illustrated in the drawings, 10 designates a suitable casing for the door lock which preferably consists of a hollow rectangular frame 11. The opposite sides of the frame 11 are connected by two parallel spaced webs 12, and the front and rear faces are closed by removable cover plates 13. One side of the frame 11 is formed with an opening 14 adapted to receive the catch 15 on the door 16.

While any suitable means can be employed to secure the casing 10 to the hatchway 17, I prefer to use bolts 18 which extend through bores 19 in the corners of the frame 11. The cover plates 13 are similar but right and left hand in construction, and the bores 19 are beveled at both ends to permit reversal of the casing 10 for doors 16 opening to the right and left.

Removably mounted on a pin 20 and between two spaced lugs 21 extending inwardly from one side of the frame 11 is a pivotal locking member or latch 22 having a hook 23 at its free end adapted to engage and retain the catch 15 when the door 16 is closed. A pair of plugs 24 are removably

threaded into tapped bores 25 in the lugs 21, and support the opposite ends of the pin 20. To permit removal of the plugs, the cover plates 13 are cut away at 26.

5 The rear end of the latch 22 is formed integral with an arm 27 extending downwardly from the pivot into a position to be engaged by the forward end of the catch 15 when the door 16 is closed. Upon being 10 thus engaged, the arm 27 will move the hook 23 into locking engagement with the catch 15, and hold the same against upward movement until the catch 15 is slightly withdrawn, as shown in Figs. 1 and 2. Downward movement of the latch 22 is arrested by a pair of lateral extensions 28 projecting toward each other from the cover plates 13. The latch 22 can be manually raised to release the catch 15 by means of a pin 29 removably secured to either side of the latch, and projecting through a suitable aperture 30 in either one of the cover plates 13, depending on which one is exposed.

Means is provided for automatically raising the latch 22. This means may be either mechanically or electrically controlled, but I have herein shown only the latter form, the mechanical form being fully disclosed and covered in my copending application, 25 Serial No. 732,398 filed August 16, 1924. Referring to Figs. 1 and 3, a ball or cam roller 31 is rotatably mounted on the pivoted end of the latch 22, and is positioned between the forked arms of a cam member 30 32 adjustably mounted on a spindle 33. One end of the spindle 33 is journaled in one side of the frame 11, the other end extends out of the casing 10 through an elongated sleeve or support 34 threaded into the other side of 35 the frame 11. A bracket 35 having a clamp sleeve 36 is adjustably and reversibly secured to the outer end of the spindle 33 and supports a magnet arm or armature 37 on its free end. The armature 37 is adapted to be attracted when the cage is at the landing by an electromagnet 38 mounted on the elevator cage 39. It will be seen that the armature 37 will raise the latch 22 upon being oscillated in either direction from a 40 central position, thereby facilitating reversal of the casing 10. Upward movement of the latch 22 is opposed by the mass of the door 16 acting through the arm 27. To prevent unlatching of the door 16 until an 45 attempt to open the latter is made, the electromagnet 38 is designed to have strength, when excited, sufficient to raise the latch 22 against its own weight but not to move the catch 15 outwardly.

50 The latch operating means is susceptible of being assembled with the lock in a number of ways to adapt the latter to different elevator installations. Thus the bracket 35 can be adjusted and reversed on the spindle 33 to properly locate the armature 37 for

different positions of the electromagnet 38 on the cage 39. The spindle 33 can also be associated with the latch 22 in any other suitable way than that shown in Fig. 1. For example, in the form shown in Fig. 2, 55 one of the plugs 24 is replaced by the sleeve 34, and the spindle 33 is substituted for the pin 20 to support the latch 22.

Means is provided for preventing movement of the cage 39 away from the landing 60 when the door 16 is open or unlatched. This means comprises a pair of rocker arms 40 and 41 made of insulating material and mounted between the webs 12 on pivot pins 42. The upper end of the rocker arm 40 is formed with a cam portion 43 adapted to be engaged and depressed by the door catch 15 as the latter enters the casing 10. The upper end of the arm 41 is provided with a projection 44 fitting loosely into a notch 45 in the lower end of the arm 27. A pair of contact strips 46 are mounted on adjacent sides of the rocker arms, and are electrically connected by a coil spring 47. Removably mounted in a pair of notches 48 formed in 65 opposite sides of the frame 11 is an insulating board 49 which supports a pair of spring contacts 50 positioned to be engaged by the contact strips 46. Undue flexing of the spring contact 50 beyond their elastic limit, as by a manual depression of the cam portion 43 or latch 22, is prevented by a pair of upstanding lugs 51 formed integral with the plate 49.

70 The contact strips 46 and the spring contacts 50 constitute a pair of switches 52 and 53 which are connected in series and are adapted to form part of one of the elevator circuits controlling the movement of the cage 39. It will be seen that upon closing and latching the door 16 both switches will be closed, and that upon subsequently deenergizing the electromagnet 38 the door 16 will be locked. When the door is open and the latch 22 is raised, both switches will be open; when the door is closed and the latch is raised, switch 53 will be open; and when the door is open and the latch 22 is down, as for example, if the electromagnet 38 became defective or deenergized, switch 52 will be open to prevent in each instance a closure of the circuit through the switches.

75 Referring to Fig. 5, I have shown the lock as forming part of a simple elevator system, but is to be understood that it can be connected in many other systems in any other suitable manner. In the present elevator system, the driving motor for the cage 39 is represented by 54, and the "up" and "down" 80 directional switches for controlling the operation of the motor by 55 and 56 respectively. These switches are adapted to be actuated by means of a car switch 57 having a suitable control lever 58.

To actuate the switch 55, the lever 58 is moved to the left, thereby closing the following circuit: from the plus main 59, through wire 60, lever 58, segmental contact 61, wire 62, coil 63, and wire 64 to the minus main 65 of the line. Closure of the switch 55, closes a circuit through the motor armature as follows: from the wire 60, through the lever 58, variable resistance 66, wire 67, switch contacts 68, wire 69, motor armature, wire 70, switch contacts 71 and wire 72 to the minus main 65. The field 73 of the motor is connected directly across the main lines by wires 72 and 74. The speed of the motor can be varied by moving the lever 58 along the resistance 66 within the range allowed by the segmental contact 61.

Movement of the lever 58 to the right, closes a circuit for the switch 56, as follows: from the plus main 59, through wire 60, lever 58, segmental contact 75, wire 76, coil 77, and wire 64 to the minus main. Operation of the switch 56 closes a circuit through the motor armature reverse to the foregoing circuit closed by the switch 55, and as follows: from the wire 60, through lever 58, resistance 66, wire 67, switch contacts 78, wire 70, motor armature, wire 69, switch contacts 79, and wire 72 to the minus main.

The switches 52 and 53 of each door lock in the hatchway are connected in series in the wire 64, and hence control the operation of the directional switches. Upon movement of the lever 58 into a neutral position to stop the cage 39, a circuit through the electromagnet 38 will be closed as follows: from wire 60, lever 58, contact 80, wire 81, coil 82, and wire 64 to the minus main. If the cage 39 is now at one of the landings 83 so as to position the electromagnet 38 next to the armature 37, the door 16 will be unlocked. Since the excitation of the electromagnet 38 is insufficient to overcome the mass of the door 16, movement of the armature 37 will be suspended until the arm 27 is released by the withdrawal of the door catch 15. Further movement of the cage 39 is prevented until the door 16 is closed and latched.

It will be seen that I have provided a door lock simple in construction and operation, capable of being assembled and mounted in different ways for different elevators, and efficient and safe in use. While I have shown the casing 10 as secured to the hatchway, and the catch 15 to the door 16, it is contemplated that these parts can readily be reversed without affecting the operation of the lock.

I claim as my invention:—

1. An elevator door lock having, in combination, a casing, a door catch, a latch in the form of a bell crank pivotally mounted in said casing, one arm of said latch being

constructed to engage said catch and the other arm being positioned to be engaged by said catch to hold said first mentioned arm in locking position, said catch having a limited movement when latched to permit release of said last mentioned arm, and means for raising said latch when said catch is moved out of engagement with said last mentioned arm.

2. An elevator door lock having, in combination, a door catch, a latch in the form of a bell crank one arm of which is constructed to engage said catch and the other arm of which is positioned to be engaged by said catch, a switch controlled by said last mentioned arm and adapted to form part of one of the control circuits of the elevator, and means for raising said latch.

3. An elevator door lock having, in combination, a casing, a door catch, a latch in the form of a bell crank one arm of which is provided with a hook to engage said catch and the other arm of which is positioned to be engaged by said catch said catch having a limited movement between said hook and said last mentioned arm, an electrical switch controlled by said catch and adapted to form part of one of the control circuits of an electrical elevator, and means for raising said latch when said catch is partially withdrawn against said hook to release said last mentioned arm.

4. An elevator door lock having, in combination, a casing, a door catch, a latch for engaging said catch, means for releasing said catch, a pair of rocker arms mounted in said casing to be actuated respectively by said catch and said latch, a pair of contact plates one on each rocker arm, said contact plates being electrically connected, a support in said casing, and a pair of spring contacts mounted on said support to be respectively engaged by said contact plates, said support comprising means for limiting the flexure of said contact plates.

5. A lock having, in combination, a casing, a door catch, a locking member for engaging said catch, a pair of rocker arms mounted in said casing and controlled by the position of said catch, contact plates on said rocker arms, and a pair of contact members mounted for engagement by said contact plates.

6. An elevator lock having, in combination, a casing adapted to receive a door catch, a latch pivotally mounted in said casing and adapted to engage said catch, a shaft journaled in said casing and extending at one side thereof, a cam member secured to said shaft and engaging said latch to raise the latter upon rotation of said shaft in either direction, a bracket adjustably and removably clamped to the outer end of said shaft, and an armature secured at one end to the free end of said bracket.

for movement therewith, said armature being adapted to be attracted by an electromagnet when the latter is in juxtaposition.

7. A lock having, in combination, a door catch, a latch adapted to engage said catch, a shaft rotatably mounted next to said latch, a bifurcated cam member mounted on said shaft and engaging said latch to move the latter out of engagement with said catch upon rotation of said shaft in either direction, and means for rotating said shaft.

8. An elevator door lock having, in combination, a casing, a member positioned to enter said casing, a latch in said casing for engaging said member, means for holding said latch in engagement with said member effective only when the door is completely closed, means rendered operative when the cage is at the landing for raising said latch but being ineffectual to do so until said first mentioned means is rendered ineffectual, and a switch controlled by said first mentioned means, said switch being adapted to form part of an elevator circuit controlling the movement of the cage.

9. A door lock having, in combination, a casing, a member positioned to enter said casing, a latch for engaging said member when the door is completely closed, and two switches one of which is actuated when said member enters the casing and the other of which is actuated when said latch engages said member.

10. An elevator door lock having, in combination, a casing, a door catch, a locking member in said casing and adapted to engage said catch, releasing means including an armature pivotally mounted on said casing and operatively connected to said locking member, and an electromagnet mounted on the cage in a position to pass adjacent said armature and attract the latter to disengage said locking member from the catch.

11. An elevator door lock having, in combination, a casing, a door catch, a locking member in said casing for engaging said catch and constructed to be held in locking position by the latter when the door is completely closed, and means for moving said locking member to release said catch, said means being rendered operable when the cage is at the landing but being ineffectual to move said member except after or simultaneously with an attempt to open the door.

12. An elevator door lock having, in combination, a catch, a locking member mounted to engage said catch, means for preventing movement of said locking member out of engagement with said catch when the door is closed, and means rendered operative when the cage is at the landing tending to move said locking member out of locking position, the action of said means being suspended until said first mentioned means is rendered ineffectual.

13. An elevator door lock having, in combination, a casing, a door catch, a latch pivotally mounted in said casing and having a depending arm to be engaged by said catch when the door is closed, cam means for engaging said latch to raise the same, an armature mounted on said casing for actuating said cam means, and an electromagnet mounted on the cage in a position to pass adjacent said armature and to attract the latter when the cage is stationary at the landing, said electromagnet being incapable of attracting said armature until said depending arm is released.

14. An elevator door lock having, in combination, a door catch, a latch mounted to engage said catch and to be held thereby from moving out of engagement therewith when the door is completely closed, and means rendered operable when the cage is at the landing to raise said latch but being ineffectual to raise said latch until said catch is partially withdrawn.

15. A door lock having, in combination, a casing, a door catch, a latch in said casing, a roller on said latch, a spindle, a cam mounted in said spindle and positioned to engage said roller to raise said latch, and means for rotating said spindle.

16. An elevator door lock having, in combination, a casing, a door catch, a latch for engaging said catch, means for holding said latch in engagement with said catch when the door is completely closed, a spindle, means on said spindle operatively connected to said latch, and means for automatically rotating said spindle when said first mentioned means is rendered ineffectual.

17. An elevator door lock having, in combination, a casing, a door catch, a latch for engaging said catch, a spindle operatively connected to said latch, means on said latch for holding said latch in engagement with said catch when the door is completely closed, and electromagnetic means rendered operable when the cage is at the landing to rotate said spindle to disengage said latch, said electromagnetic means being ineffectual to overcome said first mentioned means and acting to raise said latch only when said catch has been partially withdrawn.

18. An elevator door lock having, in combination, a door catch, a locking member for engaging said catch, means for holding said locking member in engagement with said catch when the door is completely closed, and a pair of switches controlled by said catch and said means, said switches being adapted to be connected in one of the control circuits of the elevator system.

19. An elevator door lock having, in combination, a door catch, a latch for engaging said catch, and a pair of switches respectively controlled by said catch and said latch, said switches being adapted to form

- part of the control circuits of the elevator system.
20. An elevator door lock having, in combination, a door catch, a latch for engaging said catch, said latch having a depending arm for holding it in engagement with said catch when the door is closed, and a pair of switches respectively controlled by said catch and said arm and adapted to be connected in the elevator system.
21. An elevator door lock having, in combination, a casing, a door catch, a latch in said casing for engaging said catch and adapted to be held in engagement thereby when the door is completely closed, a switch constructed to be closed by said catch as it enters said casing, and a second switch constructed to be closed when said latch engages said catch, said switches being adapted to be connected in the elevator system to control the movement of the cage.
22. An elevator door lock having, in com-
- bination, a casing, a door catch, a locking member in said casing for engaging said catch, automatic means for disengaging said locking member when the cage is at the landing, and switch means for controlling the movement of the cage, said switch means being controlled by said catch and said locking member.
23. An elevator door lock having, in combination, a casing, a door catch, a latch to engage said catch, electromagnetic means operable to raise said latch when the cage is at the landing and an attempt to open the door is made, and a pair of switches connected in series and controlled by said catch and latch, said switches being adapted to form part of the elevator system to control the movement of the cage.

In testimony whereof, I have hereunto affixed my signature.

JAMES DUNLOP.
